UNITED STATES PATENT OFFICE.

PILADE BARDUCCI, OF SECONDIGLIANO, NAPLES, ITALY.

DRYING APPARATUS.

1,409,915.

Specification of Letters Patent. Patented Mar. 21, 1922.

Application filed March 22, 1921. Serial No. 454,381.

To all whom it may concern:

Be it known that I, PILADE BARDUCCI, a subject of the King of Italy, and resident of Secondigliano, Naples, Italy, have invented 5 certain new and useful Improvements in Drying Apparatus, of which the following is a specification.

This invention relates to drying plants and has for its object a drying apparatus provided with means for causing an air stream 10 to flow through it along either of two directions perpendicular to each other.

The apparatus according to this invention may therefore be used for drying materials 15 of quite different nature, that is materials requiring to be passed through by the air flow as well as materials requiring to be leached by the air flow.

This apparatus is therefore adapted for 20 plants of small size and for travelling drying apparatus and more generally for plants in which it is desired to dry materials of different characters.

The annexed drawings show by way of 25 example an embodiment of the apparatus according to this invention; in said drawing Figure 1 is a longitudinal section on line 1-1 of Figure 2; Figure 2 is a section made, on the left hand half, along the line 2-2 of 30 Figure 1 and on the right hand half along the line 2'-2' of Figure 1; Figure 3 is an elevation and Figure 4 is a view partly in section on the line 4-4 of Figure 1.

As illustrated on the drawing, the apparatus 35 comprises two casings 1-1 having charging openings closed by doors 1' (see Figure 3) and each of said casings is divided in two chambers 2-2' which communicate with each other through an end passage 40 3 and a number of intermediate passages 4 provided in the manner hereinafter described.

At their outer sides the chambers 2-2' are 45 provided with ducts 5-5' leading to a common duct 6 in which are mounted means for promoting the air circulation; these means consist, in the embodiment illustrated on the drawing, of a propeller 7 mounted on a shaft 8 which is operated by means of the pulley 50 16 located outside the casing; in said duct 6 are also located heating means shown diagrammatically as tubes 9 in which a heating medium is caused to circulate.

At their end opposite the passages 3 each

of said chambers 2-2' is provided with a 55 port 34-34' opening into the duct 6 and controlled by a shutter 10-10' respectively, as hereinafter described.

Each shutter 10-10' is pivoted in the wall 60 of its associate chamber 2-2' in such a position as to control both the ports 34-34' of the chambers and the associate ducts 5-5', respectively; therefore either the duct 5-5' or said ports 34-34' of the chambers may be closed or opened wholly or partly. 65

Said shutters are controlled from outside by means of a gear hereinafter described.

The passages 4 through which the chambers 2-2' communicate with each other are controlled by means of a perforated plate 11 70 which is supported by a bolt 35 which is loosely engaged in a stirrup 36 by the intermediate of a spring 11'; this perforated plate may be shifted from outside by means of a controlling gear hereinafter described. 75

By assuming the perforated plate 11 be in a position to clear all the passages 4 and the shutters 10 and 10' in the position shown in full lines on the drawing, the air stream promoted by the fan 7 follows the path 80 shown by the full-line arrows in Figure 1, that is the air flows from the duct 5, passes through the duct 6, duct 5', chamber 2', passages 4, chamber 2 and returns again to the duct 5. 85

The air may also be caused to follow the same path but in a direction opposite to that shown by the arrows by reversing the operation of the fan 7.

By shifting the shutters 10-10' into the 90 position shown by dotted lines and by carrying the perforated plate 11 in a position to close the passages 4, the air stream driven by the fan is caused to follow the path shown by the dotted-line arrows in Figure 1, that is 95 the air flows in a direction in the chamber 2', passes through the end passage 3 and flows in the opposite direction in the other chamber 2. Of course also in this case the direction of the air flow in each chamber 100 may be reversed by reversing the operation of the fan, the path of the air stream being unchanged.

Therefore by this apparatus it is possible to cause the air either to act on the surface 105 of the material to be dried or to pass through it, the required operation being obtained by the manipulation of the shutters

10—10' and the perforated plate 11; further the direction of the air flow may be reversed by reversing the operation of the fan 7.

For the purpose of changing the circulating air, the duct 6 is provided with the ports 37—37' controlled by the shutters 12—12' which are arranged in such a position as to control the mouths of the ducts 13—13' which open to the outside and lead to passages 14—14' in which are located the fans 15—15' both having their blades inclined in the same direction so as to propel the air in the same direction.

When the shutters 12—12' are carried in position to close the ports 37—37' of the duct 6 the air stream promoted by the fans 15 and 15' follows the path shown by the arrows in Figure 1, that is the air passes from chamber 13 to 14 and from chamber 14' to 13' and thence to the outside; on the contrary when the shutters 12—12' are carried in position to open to a more or less large extent the ports 37—37' of the duct 6, the fan 15' drives fresh air into the duct 6 and the fan 15 draws air from 6; the air caused to circulate within the apparatus is exchanged by means of a partial supply and exhaust which are made to equal amounts so that the volume of air circulated within the apparatus by the fan 7 is unchanged.

Conveniently the air streams produced by the fans 15 and 15' have a direction opposite to that produced by the fan 7; in this manner the suction produced in the duct 6 by the fan 15 when the shutter 12 is more or less open, gives rise to the exhaust of a portion of the circulating air before it reaches the heating means 9. The fans 7—15—15' are all mounted on the same shaft 8 and the fans 15—15' have their blades inclined in an opposite direction with regard to the blades of the fan 7; therefore when the operation of the fan 7 is reversed, is similarly reversed the operation of the fans 15—15' and then the exhaust is made by the fan 15' and the suction or supply is made by the fan 15, the above stated conditions being always complied with.

The above described arrangement of the fans is the preferred one as it shows large facilities for the manufacture and operation of the apparatus, but of course the fans may be arranged and controlled in different manners and may be independent from each other.

This invention provides also a controlling device for the shutters 10—10' as well as for the perforated plate 11 which are required to be operated at the same time; this device is shown by Figure 3.

Said device comprises fork-shaped arms 17—17' each secured on the spindles 38—38' of one of said shutters 10—10' and arms 18—18' loose on said spindles and having their outer end engaged between two springs

39—39 mounted in said fork arms 17—17'; to each of the arms 18—18' is connected a lever 19—19' pivoted at 20—21 respectively.

Said levers 19—19' are in turn connected with a screw-threaded spindle 21 actuated by a hand wheel 22 and one of said levers, 19', is solid with a shaft 23 on which are secured arms 24 pivotally connected with tails 25 of the perforated plate 11 (see Figure 1).

By operating the hand wheel 22 the perforated plate 11 is shifted and at the same time the shutters 10—10' are rotated in opposite directions. The described spring connection of the shutter shafts with the levers 18—18' makes it possible to impart to these latters a larger displacement than that made by the shutters and the fork arms 17—17' solid therewith, so that either of the springs 39 are tensioned and the shutters may be forced against the edges of the associated port.

The spindles of shutters 12—12' for the air exhaust and supply are provided with arms 28—28' controlled by rods 27—27' which are operated by a single handle 26.

Within the chambers 2—2' are arranged the supporting means for the material to be dried; in the embodiment illustrated said supporting means consist of section bars 29 adapted to support both frames 30 and rods 31 but of course any other arrangement may be used.

The partition between the adjacent chambers 2—2' is preferably provided by two parallel rows of bars 32 to which are secured the section bars 29 above referred to; said bars 32 are spaced from each other to provide intermediate passages 4 and the two rows provide and intermediate space in which is located the perforated plate 11.

This plate 11 is provided with slots 40 having the same size as the bars 32 so that said slots 40 and the passages 4 are closed when the slots 40 are carried in register with the bars 32.

Partitions 33 are preferably located within the ducts 5—5' said partitions being inclined downwards and acting to evenly distribute 115 the air supply through said ducts to chambers 2—2' connected therewith.

In the construction illustrated on the drawing the apparatus comprises two casings 1—1 coupled with each other but of course it 120 may comprise either a single casing or any number of them, being only essential that the internal space of each casing be divided in two chambers by a partition leaving a large passage near one end and provided with a 125 number of intermediate passages and with shutting means therefor, and that both chambers be connected, at their ends opposite to said large passage of their intermediate partition, with a duct in which an air flow is 130

promoted and be provided with means for causing the air to flow through said chambers in either of two directions substantially perpendicular to each other.

5 It is to be understood that a number of modifications may be made in the described construction, particularly as to the mounting of the fans and the controlling means for the shutters, this invention being only 10 defined by the appended claims:—

What I claim as my invention and desire to secure by United States Letters Patent is:—

1. A drying apparatus comprising a casing, means dividing said casing into two adjacent chambers, said means providing a large passage near one end of said chambers and intermediate passages interconnecting said chambers, means in said chambers for supporting the material to be dried, a duct 20 opening at the opposite sides of said adjacent chambers remote from each other, this duct having ports opening into said chambers at their ends opposite to said large end passage, means for causing air to circulate 25 through said duct and chambers, means controlling the communication of said ducts and ports with said chambers and means controlling said intermediate passages of said dividing means between said chambers.

30 2. A drying apparatus comprising a casing, means dividing said casing into two adjacent chambers said means providing a large passage near one end of said chambers and intermediate passages interconnecting 35 said chambers, means in said chambers for supporting the material to be dried, a duct opening at the opposite sides of the said adjacent chambers remote from each other, this duct having ports opening into said chambers at their ends opposite to said large end 40 passage, reversible means for causing air to circulate through said duct and chambers, means controlling the communication of said duct and ports with said chambers and means 45 controlling said intermediate passages of said dividing means between said chambers.

3. A drying apparatus comprising a casing, means dividing said casing into two adjacent chambers, said means providing a 50 large passage near one end of said chambers and intermediate passages interconnecting said chambers, means in said chambers for supporting the material to be dried, a duct opening at the opposite sides of said adjacent chambers remote from each other, this duct having ports opening into said chambers at their ends opposite to said large end passage, means for causing air to circulate through said duct and chambers, 55 means controlling the communication of said duct and ports with said chambers, means controlling said intermediate passages of said dividing means between said chambers and means for operating said controlling means.

60 65 4. A drying apparatus comprising a cas-

ing, means dividing said casing into two adjacent chambers, said means providing a large passage near one end of said chambers and intermediate passages interconnecting said chambers, means in said chambers for supporting the material to be dried, a duct opening at the opposite sides of said adjacent chambers remote from each other, this duct having ports opening into said chambers at their ends opposite to said large end passage, means for causing air to circulate through said duct and chambers, means controlling the communication of said duct and ports with said chambers, means controlling said intermediate passages of said dividing means between said chambers, means for operating said controlling means and means for supplying and exhausting air to and from said duct and chambers.

5. A drying apparatus comprising a casing, means dividing said casing into two adjacent chambers, said means providing a large passage near one end of said chambers and intermediate passages interconnecting 90 said chambers, means in said chambers for supporting the material to be dried, a duct opening at the opposite sides of said adjacent chambers remote from each other, this duct having ports opening into said chambers at their ends opposite to said large end passage, heating means in said duct, means for causing air to circulate through said duct and chambers, means controlling the communication of said duct and ports with said 100 chambers and means controlling said intermediate passages of said dividing means between said chambers.

6. A drying apparatus comprising a casing, means dividing said casing into two adjacent chambers, said means providing a large passage near one end of said chambers and intermediate passages interconnecting said chambers, means in said chambers for supporting the material to be dried, a 105 duct opening at the opposite sides of said adjacent chambers remote from each other, this duct having ports opening into said chambers at their ends opposite to said large end passage, heating means in said duct, means for causing air to circulate through said duct and chambers, means controlling the communication of said ducts and ports with said chambers, means controlling said intermediate passages of said dividing means between said chambers, and means for supplying and exhausting air to and from said duct and chambers.

7. A drying apparatus comprising a casing, means dividing said casing into two adjacent chambers said means providing a large passage near one end of said chamber and intermediate passages interconnecting said chambers, means in said chambers for supporting the material to be dried, a duct 125 130

- opening at the opposite sides of said adjacent chambers remote from each other, this duct having ports opening into said chambers at their ends opposite to said large end passage,
- 5 the ends of said chambers at which are provided said passages and ports lying on a line substantially perpendicular to the line on which lye the sides of said chambers connected with said duct, means for causing air
- 10 to circulate through said duct and chambers, means controlling the communication of said ducts and ports with said chambers and means controlling said intermediate passages of said dividing means between said chambers.
- 15 8. A drying apparatus comprising a casing, means dividing said casing into two adjacent chambers said means providing a large passage near one end of said chambers and intermediate passages interconnecting said chambers, means in said chambers for supporting the material to be dried, a duct leading to passages provided in the opposite sides of said adjacent chambers remote from each
- 20 other, this duct having ports opening into said chambers at their ends opposite to said end large passage, the ends of said chambers at which are provided said large passage and ports lying on a line substantially perpendicular to the line on which lye said sides of said chambers, means controlling the communication of said duct and ports with said chambers, means controlling said intermediate passages and means operating said controlling means, these operating and controlling means closing said end ports when said side passages and intermediate passages are open and opening said end ports when said side and intermediate passages are closed.
- 25 9. A drying apparatus comprising a casing, means dividing said casing into two adjacent chambers said means providing a large passage near one end of said chambers and intermediate passages interconnecting said chambers, means in said chambers for supporting the material to be dried, a duct leading to passages provided in the opposite sides of said adjacent chambers remote from each other, this duct having ports opening
- 30 into said chambers at their ends opposite to said large end passage, means controlling the communication of said duct and ports with said chambers, means controlling said intermediate passages and means operating said controlling means, these operating and controlling means closing said end ports when said side passages and intermediate passages are open and opening said end ports when said side and intermediate passages are closed.
- 35 10. A drying apparatus comprising a casing, transverse bars dividing said casing into chambers, said bars being arranged in two rows providing an intermediate space
- 40 between said rows and the bars of each

row being spaced apart from each other to provide passages interconnecting said chambers and a large passage interconnecting said chambers at one of their ends, a partition mounted between said two rows of 70 bars and having slots adapted to register with said intermediate passages, means in said chambers for supporting the material to be dried, a duct opening at the opposite sides of said adjacent chambers remote 75 from each other, this duct having ports opening into said chambers at their ends opposite to said large end passage, means for causing the air to circulate through said duct and chambers, means controlling the 80 communication of said duct and ports with said chambers, means operating said controlling means and means for shifting said slotted partitions, these controlling and shifting means closing said ports when said side and intermediate passages are open and opening said ports when said side and intermediate passages are closed.

11. A drying apparatus comprising a casing, means dividing said casing into two adjacent chambers, said means providing a large passage near one end of said chambers and intermediate passages interconnecting said chambers, means in said chambers for supporting the material to be dried, a duct opening at the opposite sides of said adjacent chambers remote from each other, this duct having ports opening into said chambers at their ends opposite to said large end passage, a fan mounted in said 90 duct for causing air to circulate through said duct and chambers, channels adjacent to said duct, this duct having ports opening in said channels at the opposite sides of said fan, controlling means for said ports 95 these controlling means being interconnected to control together said ports in the same manner, propellers mounted in said channels and solid with said fan, these propellers driving air currents in a direction 100 opposite to that of the air driven in said duct by said fan, means controlling the communication of said duct and ports with said chambers, means controlling said intermediate passages and means for operating said 105 controlling means.

12. A drying apparatus comprising a casing, means dividing said casing into two adjacent chambers, said means providing a large passage near one end of said chambers and intermediate passages interconnecting said chambers, means in said chambers for supporting the material to be dried, a duct having mouths opening into the opposite sides of said adjacent chambers, baffles in 110 said mouths of said duct for distributing the air over said mouths, this duct having ports opening into said chambers at their ends opposite to said large passage, a fan mounted in said duct between said ports, 115

shutters mounted at said ports and adapted to close either said ports or said mouths, a slotted partition controlling said intermediate passages, means operating said shutters and said partitions to close and open at the same time said intermediate passages and said mouths and to open and close at

the same time said ports, means for supplying and exhausting equal amounts of air to and from said duct at the opposite side 10 of said fan and heating means in said duct.

Signed at Turin, Italy, this 23d day of Feb., 1921.

PILADE BARDUCCI.
